Primary Examiner — Clare E Heflin*(74) Attorney, Agent, or Firm* — Saidman DesignLaw Group, LLC(57) **CLAIM**

The ornamental design for a light, as shown and described.

DESCRIPTION

FIG. 1 is a perspective view of a light showing our new design;

FIG. 2 is another perspective view thereof;

FIG. 3 is a front elevational view thereof;

FIG. 4 is a rear elevational view thereof;

FIG. 5 is a left side elevational view thereof, the right, top, and bottom side views being identical thereof;

FIG. 6 is a perspective view of a second embodiment thereof;

FIG. 7 is another perspective view thereof;

FIG. 8 is a front elevational view thereof;

FIG. 9 is a rear elevational view thereof; and,

FIG. 10 is a left side elevational view thereof, the right, top, and bottom side views being identical thereof.

The broken lines depict portions of the light that form no part of the claimed design.

1 Claim, 10 Drawing Sheets(56)
